UNITED STATES PATENT OFFICE

2,448,546

PORTABLE RECOMPRESSION CHAMBER

Lawrence M. Plemel and Bill J. Abernathy, Jr.,
United States Navy

Application September 4, 1945, Serial No. 614,326

3 Claims. (Cl. 128—204)

(Granted under the act of March 3, 1883, as
amended April 30, 1928; 370 O. G. 757)

1

This invention relates to a portable recompression chamber for the treatment of caisson disease or for other purposes usually served by large complicated installations of a permanent nature.

In locations where much diving activity is in progress, it is usual to provide a compression chamber with medical facilities and all other appurtenances necessary for the care of divers. These standard chambers are heavy and cumbersome as well as expensive, and many such activities have too little diving to support their use. However, when even one man is incapacitated by the "bends" or caisson disease, it is necessary for him to have prompt treatment. In such cases it may be difficult, if not impossible, to provide such treatment early enough to secure the best results therefrom. Routine diving, also, involves controlled decompression at times. It is with these things in mind that we have designed the present portable chamber.

An object of the invention is to provide an improved chamber suitable for the accommodation of one diver and having the essential elements necessary for minimum care.

A further object of the invention is to provide a recompression chamber portable by virtue of its small size and inexpensive so that such chambers may be distributed to activities carrying on a small amount of diving or, for emergency use, be transportable by aircraft or other light forms of transportation.

With these objects and others in view, we have designed the chamber which is the subject of the following description in which:

Figure 1 is an isometric view of the entire device with all elements visible from the outside shown; and

Figure 2 is an internal view taken as if the end opposite the entrance hatch were removed.

The body or casing of the chamber is indicated by the reference character 1. For entry into the chamber a main hatch 2, supported by the hatch arm 3, hinge 4 and ball and socket joint 5, is provided in one end. The hatch is of the internal sealing type, elliptical in plan. Hatch dogs 6 are provided to secure the hatch in proper position while pressure is developed inside the chamber. The dogs are operated by handle 7, and a gasket 8 provides fluid tight fit. The dogs fit into notches 6a to properly position the elliptical hatch when it is closed.

For the insertion of medical and/or other supplies such as foods, there is provided a medical lock generally referred to at 9. This lock com-

prises a cylindrical chamber passing through the body 1. The upper or outside end of the lock is provided with a hatch 10 operable from outside, and a valve 11. At the lower or internal end of the lock is a second hatch 12 with a valve 13. Inside the lock there is a tray 14 provided for use in lowering such articles as are desired through the lock to the occupant of the chamber. The tray is supported by slideable legs 14a. The hatch is suspended by one of two arms 14b and can be closed by swinging it until its lateral extension 12a hooks into engagement with the other arm.

At the end opposite the entrance hatch, or in any suitable place, there is provided a stuffing box 15 for sealed entry of electrical cables providing for telephone, light and other desired services. Hand rails 16 and hoisting tabs 17 are provided for convenient handling of the chamber. Observation ports 18 are provided in such location to allow observation by or of the patient.

Oxygen (air) is provided by apparatus generally referred to at 19. This apparatus comprises oxygen inlet valve 20, regulator 21 in a by-pass pipe and the connection T 22. Exhaust is by means of system 23 which comprises the exhaust valve 24 and a by-pass having a regulator 25. Pressure gauge 26 is in addition to the regulator gauges and is designed for indicating internal pressure either in pounds per sq. inch or in ft. of depth. Rails 27 are provided for support and easy entry and exit of a stretcher, not shown.

In use, the chamber having been established at a point close to the operations so that prompt attention may be given to any diver in need, the patient will be placed upon a stretcher and inserted into the chamber, head first. Upon closing the main and medical lock hatches and valves, air pressure from a suitable supply may be established in the chamber by operation of the supply system 19. To secure air for breathing while maintaining the proper pressure the exhaust system 23 will be suitably controlled. Easy observation of the pressure conditions is assured by the various valves, regulators and gauges. If it is desired to give the patient food, it is necessary for the upper medical lock hatch to be opened. To do this, pressure is relieved from the hatch by opening valve 11, whereupon hatch 10 may be removed and articles of food placed upon the tray 14. The hatch and valve will then be closed, and the patient may, by first opening valve 13 to equalize pressure in the lock, remove the hatch 12. He may then allow the tray to descend and remove the articles from it.

If desired, internal lights may be provided, as

may telephone service for voice communication with the patient.

It is contemplated that the device described will be valuable in emergency service wherein, after securing the patient comfortable and with suitable pressure in the small chamber, it may, with the patient, be transported to a location providing full facilities. In this way there will be gained the advantage inherent in great promptness of attention.

It will now be apparent that we have provided a useful and convenient portable recompression chamber. Of course, many changes will be possible in the exact arrangement and in details, without departing from the spirit of our invention, which is expressed in the terms of the following claims.

This invention may be made or used by or for the Government of the United States for governmental purposes without the payment to us of any royalties thereon or therefor.

What is claimed is:

1. In a portable recompression chamber, a casing having a substantially elliptical open end with notches in the periphery of the opening, and a closure device having an arm pivoted to said casing adjacent said opening; said device comprising a substantially elliptical plate universally connected to said arm so that it can be moved into the interior of said casing, and a quick-acting toggle mechanism upon said plate and comprising elements shiftable into said notches to position said plate when it is closed.

2. In a recompression chamber, a casing having an opening and closure means associated therewith, and an air lock unit fitted to a wall of said casing, said unit comprising a tube extending through said casing and open at both ends, a tray within said tube and movable into said casing, an externally operable means for closing the outer end of said tube, and means for closing the inner end of said tube.

3. In the apparatus defined in claim 2, said means for closing the inner end of said tube comprising a pair of rigid arms within the casing, and a plate swingingly suspended by one of said arms and movable into latched engagement with the other arm.
